LOCK STITCH SEWING MACHINE

George Sauer, Berwyn, Ill., assignor to Union
Special Machine Company, Chicago, Ill., a cor-
poration of Illinois

Application March 19, 1934, Serial No. 716,415

6 Claims. (Cl. 112—220)

The invention relates to new and useful improvements in a sewing machine and more particularly to a lock stitch sewing machine, wherein the stitches are formed through the cooperative action of a needle and a rotary hook.

An object of the invention is to provide a machine of the above type, wherein the actuated parts of the stitch forming mechanism and the actuated parts of the feeding mechanism are all operated from shafts which terminate at the standard and wherein said shafts are interconnected at said standard.

A further object of the invention is to provide a machine of the above type, wherein the interconnecting parts for the shafts are in the form of intermeshing gears, one of which may be positioned so as to run in an oil bath at the lower end of a hollow enclosed standard.

In the drawings—

Figure 1 is a vertical sectional view longitudinally through a machine embodying the improvements:

Fig. 2 is an end view of the machine as viewed from the right, with parts broken away to show the gearing at the standard, and

Fig. 3 is a view partly in plan and partly in section looking down on the machine from above the work support and with parts of the work support broken away to show the structure beneath the same.

The invention is shown as applied to a sewing machine which includes a hollow standard closed at its lower end, to which is connected a work support disposed above the lower end of the standard. Beneath the work support is the feeding mechanism which includes a feed bar deriving its feeding movements from a rotating shaft located beneath the work support and extending into the standard. Also located beneath the work support is a rotating hook which is operated from an actuating shaft extending into the standard. Connected to the upper end of the standard is an overhanging arm carrying a needle head in which a needle bar reciprocates. The needle bar is actuated from a shaft located in said arm and extending into said hollow standard.

In the present illustration of the invention, the shaft in the overhanging arm is the main actuating shaft and it carries a gear which meshes with a transmitting gear located in the hollow standard and journaled on a shaft fixed to the standard. This transmitting gear meshes with a gear on the end of the feed actuating shaft and there is a gear on the end of the rotary hook actuating shaft which meshes with the gear on the feed

shaft. Thus it is that the driving gears for interconnecting the three shafts, are all located in the hollow standard. The gear for driving the feed shaft is disposed relative to the bottom portion of the standard so that it runs in an oil bath in said standard and thus it is that the gears are all lubricated through this gear on the feed shaft.

Referring more in detail to the drawings, the invention is shown as applied to a sewing machine which includes a hollow standard 1, having spaced walls 2 and 3 at the lower end thereof which are joined by the usual side walls and all of these walls are connected by a plate 4, which completely houses the lower end of the standard and forms an oil sump in which an oil bath may be maintained. Preferably formed integral with the hollow standard and projecting laterally therefrom, is a work supporting member 5. Also connected to said hollow standard and projecting laterally therefrom is a hollow arm 6 which overhangs the work support 5. At the outer end of this arm 6 is a needle head 7 in which a needle bar 8 reciprocates. Said needle bar carries a needle 9. A main actuating shaft 10 is mounted in a bearing 11 in the overhanging arm and a bearing 12 in the standard. This main actuating shaft 10 carries a crank disk 13 at the needle head which is connected by means of a link 14 to the needle bar for reciprocating the same.

Cooperating with the needle beneath the work support is a rotary hook 15. Said rotary hook 15 is fixed to the end of an actuating shaft 16. This actuating shaft 16 is mounted for rotation in a bearing sleeve 17 carried by a bearing lug 18, which is formed integral with the work support 5. The shaft at its inner end extends through the wall 2 of the standard into the hollow standard. There is a bushing 19 which together with the shaft closes the opening through which the shaft passes. The material is fed across the work support by a feed dog 20 carried by a feed bar 21 which is attached to a feed rocker 22. The feed bar is moved back and forth and is raised and lowered by an actuating shaft 23 located beneath the work support; said shaft carries an eccentric with which an eccentric strap 24 cooperates and said eccentric strap is provided with a member 25 which telescopes within an arm 26 pivoted to the feed rocker. Pivoted to this arm is a link 27 which in turn is pivoted to a member 28 fixed to a shaft 29. As the shaft rotates the eccentric strap will impart lateral movement to the arm 26 and as the arm 26 swings on its pivotal connection to the feed rocker, it will be caused by the link 27 to move endwise and thus impart a feeding move-

ment to the feed dog. The feed bar is raised and lowered by an eccentric strap 30 which is connected to the feed bar in the usual manner. The specific form of feeding mechanism just referred to, forms no part of the present invention, but is shown, described and claimed in the application filed by George Sauer and Clarence C. Smith, on May 31, 1933, Serial No. 673,738.

The actuating shaft 23 for the feed bar extends 10 through the wall 2 of the housing and rotates in a bushing 31 which together with the shaft closes the opening through which the shaft extends. On the inner end of this shaft 23 is a gear 32. The gear 32 meshes with a transmitting gear 33 15 carried by a hub 34 journaled on a fixed shaft 35 mounted in the hollow standard. The gear is prevented from lateral movement on the shaft by collars 36, 36 fixed to the shaft. This gear 33 meshes with a gear 37 which is fixed to the shaft 20 10. On the outer end of the shaft 10 is a belt wheel 38.

On the end of the shaft 16 and located in the hollow standard is a gear 39 which meshes with the gear 32 on the feed shaft.

25 From the above it will be apparent that the two actuating shafts for the stitch forming mechanism, that is, the shaft which actuates the needle and the shaft which actuates the rotary hook, both extend into the hollow standard. Likewise the shaft which actuates the feeding mechanism and imparts all movements thereto, extends into the hollow standard and these three shafts within the hollow standard are interconnected by intermeshing gears so that they are all positively rotated in a certain timed relation to each other. The gear on the main actuating shaft and the gear on the feed shaft both mesh with the transmitting gear and are so dimensioned that the main actuating shaft and the feed shaft will 30 40 turn in unison and in the same timing. The gear on the rotary hook shaft is dimensioned so that this shaft is given two rotations for each rotation of the feed shaft. By this arrangement of the rotary hook shaft, so that the gear which actuates 45 the shaft meshes directly with the actuated gear of the feed shaft, all strain is taken off the feed shaft and the gear connection for driving the rotary hook has a direct connection to the shaft which drives the needle bar so that these two 50 55 shafts will be maintained in their set timed relation to each other. Furthermore, where the gears which drive the actuating parts are all located in the hollow standard, they may be readily lubricated by running the lowermost gear in an oil bath.

The transmitting gear 33 is given a number of teeth which is not a multiple of the gears with which it meshes. A progressive shifting engagement is, therefore, obtained so that a tooth of 30 either the gear 31 or 32 which is subject to special strain, will find itself in contact successively with a different tooth in the transmitting gear. This lessens the wear, but a still more effective distribution of wear is obtained by making the material of the teeth of the transmitting gear softer than the material of the teeth of the other gears, as for example, bakelite, thus producing the greatest wear on the teeth which have only intermittent contact with the tooth subject to special strain. This arrangement of the teeth in the driving train of gears, and the general type of machine to which this invention is applied, is shown and described more fully in the application of Norman V. Christensen and Charles F. 65 70 75 Rubel, filed May 9, 1933, Serial No. 670,186. While

the invention is described as embodied in a sewing machine having a hollow enclosed standard, with an oil sump for lubricating the intermeshing gears, it will be understood that from certain aspects of the invention, the driving mechanism for the needle, the feed and the looper, which is shown and described, may be used in other types of machines. It is also obvious that minor changes in the details of construction may be made without departing from the spirit of the invention as set forth in the appended claims.

Having thus described the invention, what I claim as new and desire to secure by Letters Patent, is—

1. A sewing machine including in combination, 15 a standard, a work support, an arm overhanging the work support, a needle bar carried by said arm, a feeding mechanism and a rotary hook beneath the work support, a transmitting gear carried by the standard, an actuating shaft for the 20 needle bar geared to the transmitting gear, another actuating shaft for the feeding mechanism geared to the transmitting gear, and another actuating shaft for the rotary hook directly geared to the actuating gear for the feed operating shaft. 25

2. A sewing machine including in combination, a standard, a work support, an arm overhanging the work support, a needle bar carried by said arm, a feeding mechanism and a rotary hook beneath the work support, a transmitting gear 30 carried by the standard, an actuating shaft for the needle bar disposed in said overhanging arm and extending across said standard and having a gear meshing with the transmitting gear in the standard, an actuating shaft for the feeding mech- 35 anism extending into said standard and carrying a gear meshing with the transmitting gear in said standard, an actuating shaft for the rotary hook extending into said standard and carrying a gear directly meshing with the actuating gear for the 40 feed shaft, all of said gears within said standard being disposed for rotation in substantially the same plane.

3. A sewing machine including in combination, 45 a hollow standard closed at its lower end, a work support connected thereto and disposed above the lower end of the standard, an arm carried by the standard and overhanging said work support, a needle bar mounted for reciprocation on said arm, an actuating shaft for the needle bar mounted in 50 said arm and extending into said standard, a feeding mechanism beneath the work support, an actuating shaft therefor disposed beneath the work support and extending into said hollow standard, a rotary hook beneath the work support, an actuat- 55 ing shaft therefor extending into said hollow standard, and means located within the hollow standard and interconnecting said shafts.

4. A sewing machine including in combination 60 a hollow standard closed at its lower end, a work support connected thereto and disposed above the lower end of the standard, an arm carried by the standard and overhanging said work support, a needle bar mounted for reciprocation on said arm, an actuating shaft for the needle bar mounted in 65 said arm and extending into said standard, a feeding mechanism beneath the work support, an actuating shaft therefor disposed beneath the work support and extending into said hollow standard, a rotary hook beneath the work sup- 70 port, an actuating shaft therefor extending into said hollow standard, a gear connected to the needle actuating shaft and disposed in said standard, a gear connected to the actuating shaft for the feeding mechanism and disposed in said 75

standard, a transmitting gear intermeshing with said gears for imparting rotation of one shaft to the other, a gear on said hook actuating shaft located in said standard and meshing with the gear on said feed actuating shaft, said last-named gear being dimensioned so that said hook actuating shaft is rotated twice for each rotation of the feed shaft.

5. A sewing machine including in combination
10 a hollow standard closed at its lower end, a work support connected thereto and disposed above the lower end of the standard, an arm carried by the standard and overhanging said work support, a needle bar mounted for reciprocation on said arm, an actuating shaft for the needle bar mounted in said arm and extending into said standard, a feeding mechanism beneath the work support, an actuating shaft therefor disposed beneath the work support and extending into said
15 hollow standard, a rotary hook beneath the work support, an actuating shaft therefor extending into said hollow standard, a gear connected to the needle actuating shaft and disposed in said standard, a gear connected to the actuating shaft for the feeding mechanism and disposed in said standard, a transmitting gear intermeshing with
20 said gears for imparting rotation of one shaft to
25

the other, a gear on said hook actuating shaft located in said standard and meshing with the gear on said feed actuating shaft, said last-named gear being dimensioned so that said hook actuating shaft is rotated twice for each rotation of the feed shaft, all of said gears being disposed for rotation in the same plane and said gear for actuating said feed shaft being disposed so as to rotate beneath the surface of an oil bath in said hollow standard.

6. A sewing machine including in combination a standard, a work support, an arm overhanging the work support, a needle bar carried thereby, a feeding mechanism and a rotary hook beneath the work support, a transmitting gear carried by the standard, an actuating shaft for the needle bar, a gear carried thereby and meshing with said transmitting gear, an actuating shaft beneath the work support for the feeding mechanism, a gear carried thereby and meshing with the transmitting gear, an actuating shaft for the rotary hook, and a gear carried thereby meshing with the actuating gear for the feed operating shaft, all of said gears being disposed in a single plane.
